NEW ANTIBACTERIAL COMPOUNDS

Gaetano Melone and Alberto Vecchi, Milan, Italy, assignors to Lepetit S.p.A., Milan, Italy
No Drawing. Filed Sept. 13, 1957, Ser. No. 683,717
Claims priority, application Italy Sept. 14, 1956
7 Claims. (Cl. 167—58)

The present invention relates to new antibacterial compounds. More particularly the compounds with which the invention is concerned correspond to the following generic formula:

wherein X represents a sulfur atom or a vinylene group —CH=CH—.

The compounds of this invention have been found particularly useful against a series of gram-positive and gram-negative bacteria. They were tested against 35 species of bacteria and fungi in fluid medium. The bacterial sensitivity tests on most strains were carried out in Penassay broth Difco. The tests on *M. flavus*, *S. hemolyticus*, *D. pneumoniae* and *Brucella abortus* were carried out in Brain Heart Infusion Difco. The Myc. tuberculosis H37Rv strain was tested in Proskauer-Beck medium having the following composition: Asparagine 5 g., KH₂PO₄ 5 g., K₂SO₄ 0.5 g., glycerol 20 ml., trimagnesium citrate 1.5 g., H₂O 800 ml., horse serum 100 ml. The paratubercular strains were tested in TB broth base with 5% glycerol and 10% Dubos medium albumin. The antifungal tests were made in Sabouraud medium of the following composition: peptone 10 g., dextrose 40 g., H₂O 1000 ml. The minimal inhibiting concentrations in $\mu\text{g./ml.}$ are expressed in Table I. The readings were made after 18 hrs. for bacteria and 40 hrs. for fungi.

TABLE I

Spectrum of antibacterial and antimycotic activity
[Minimum inhibitory concentration $\mu\text{g./ml.}$]

	(1) 2-bromo-4'-cyano-cinnamaldehyde	(2) α -Bromo- β -(5-cyano-2-thienyl)-acrolein
<i>M. aureus</i>	10	5
<i>M. flavus</i>	5	5
<i>Sarc. lutea</i>	10	10
<i>Str. hemolyticus</i>	10	10
<i>Streptococcus faecalis</i>	20	20
<i>Dpl. pneumoniae</i>	2	10
<i>E. coli</i>	10	20
<i>Klebs. pneumoniae</i> (non caps.)	10	20
Do	20	50
<i>Sh. sonnei</i>	20	50
<i>Salm. typhi</i>	5	10
<i>Pr. vulgaris</i>	5	10
<i>Pseud. aeruginosa</i>	50	10
<i>Bruc. abortus</i>	10	5
<i>Bac. subtilis</i>	5	5
<i>Bac. cereus</i>	5	10
<i>Bac. anthracis</i>	5	5
<i>Myc. phlei</i>	10	5
<i>Myc. ranae</i>	10	10
<i>Myc. minetti</i>	20	10
<i>Myc. 607</i>	10	20
<i>Myc. tuberculosis</i> H37Rv	5	5
<i>Nocardia asteroides</i>	10	5
<i>Sacchar. cerevisiae</i>	0.5	1
<i>Kloeckera brevis</i>	0.5	0.5
<i>Candida albicans</i> ATCC 10231	5	5
<i>Candida albicans</i> SKF 2270	5	5
<i>Cryptococcus neoformans</i>	1	2
<i>Aspergillus niger</i>	20	20
<i>Penicillium</i> sp.	5	2
<i>Histoplasma capsulatum</i>	0.5	0.5
<i>Trich. mentagri</i> ATCC 8757	0.5	2
<i>Trich. mentagri</i> SKF 17410	2	0.5
<i>Trichophyton schoenleinii</i>	2	1
<i>Trichophyton culanum</i>	2	1

2

The compounds were tested also on experimental animals and found very active. Furthermore their toxicity was found to be very low, ranging between 700 and 1000 mg./kg. in mice, rats and rabbits on administration by 5 oral route, and between 200 and 350 mg./kg. by intraperitoneal route.

The topical use of the compounds of the invention on humans was successful, giving substantial improvement in most skin infections due to the organisms reported in 10 Table I. The compounds were applied in the form of ethyl alcohol solutions containing 1 mg./ml. or in ointments containing 1—10% of the active ingredient incorporated in one or more of the common ointment bases, such as Vaseline, lanolin, etc.

15 The method for preparing the compounds of the invention starts from 4-cyanobenzaldehyde or from 5-cyano-2-thiophenecarboxaldehyde. While 4-cyanobenzaldehyde is already known in the chemical literature, 5-cyano-2-thiophenecarboxaldehyde has been prepared by us from 20 2-methyl-5-iodothiophene which with cuprous chloride in alkaline medium is transformed into 5-cyano-2-thiophenecarboxaldehyde as described in one of the examples of the present application. Cyanobenzaldehyde or cyanothiophenecarboxaldehyde are then refluxed with acetaldehyde 25 in the presence of acetic anhydride for about one hour; on cooling, the condensation product precipitates, i.e. 4'-cyanocinnamaldehyde or β -(5-cyano-2-thienyl)-acrolein. These compounds are converted into the other compounds of the generic formula by introduction of an halogen into 30 position α .

The α -bromination is carried out under particular conditions. By treatment with one mole of bromine saturation of the double bound occurs with formation of the α,β -dibromoderivative. This latter is treated with an 35 alkali metal carbonate without isolating it from the reaction medium, whereby the desired α -bromoacrolein is obtained.

This invention is illustrated by the following examples which, nevertheless, are not intended to limit the same.

40 **EXAMPLE I**

A mixture of 20 g. 5-iodo-2-methylthiophene, 190 cc. anhydrous pyridine and 14.3 g. cuprous cyanide is refluxed for 8 hours. The pyridine is then distilled off in vacuo, the residue is extracted with ethyl acetate, the extract is dried and after evaporating the solvent in vacuo the residue is fractionated, the product being collected 45 at 87° C. under 1 mm. Yield 8.5 g. (77%) of 5-cyano-2-methylthiophene, n_{D}^{20} 1.565.

To a mixture of 13.5 g. 5-cyano-2-methylthiophene, 50 171 cc. glacial acetic acid and 169.5 cc. acetic anhydride, 25.5 cc. concentrated sulfuric acid are slowly added, without exceeding 25° C. followed by 30 g. chromic anhydride, added at small portions and keeping the temperature between 5 and 10° C. The mixture is stirred 55 for some minutes, then it is poured in about twice its volume of ground ice. The light yellow precipitate is collected in vacuo and dried. Yield 18 g. (69%) of 5-cyano-2-thiophenecarboxaldehyde diacetate, M.P. 77—78° C.

60 To a mixture of 140 cc. 95% ethyl alcohol, 140 cc. water and 35 g. 5-cyano-2-thiophenecarboxaldehyde diacetate, 10.5 ml. concentrated sulfuric acid is quickly added, then the mixture is refluxed till a complete solution results (about 20 minutes). On cooling, 5-cyano- β -thiophenecarboxaldehyde precipitates which is collected 65 in vacuo, washed with water and dried. Yield 18 g. (90%); M.P. 93—94° C.

A mixture of 34.2 g. 5-cyano-2-thiophenecarboxaldehyde and 100 ml. acetaldehyde is cooled between 6 and 70 8° C., and at this temperature 5 ml. of a 25% potassium hydroxide solution in anhydrous methanol are added. After addition of 100 ml. acetic anhydride the mixture

3

is refluxed for one hour, then it is cooled, a solution of 35 ml. concentrated hydrochloric acid in 300 ml. of water is added, the mixture is again refluxed for 30 minutes and cooled. The precipitate is washed with water and recrystallized from water. Yield 27 g. (66%) of β -(5-cyano-2-thienyl)-acrolein, M.P. 128-129° C.

To a solution of 94 g. β -(5-cyano-2-thienyl)-acrolein in 720 cc. of glacial acetic acid, kept at a temperature between 33 and 35°, 32 ml. of bromine are added in small portions. To the obtained solution 40 g. potassium carbonate are gradually added. When the addition is complete the mixture is refluxed for 30 minutes. On cooling, α -bromo- β -(5-cyano-2-thienyl)-acrolein precipitates which is collected in vacuo and recrystallized from 95% ethyl alcohol. Yield 116 g. (83%); M.P. 153-155° C.

EXAMPLE 2

To a solution of 32.7 g. 4-cyanobenzaldehyde in 100 ml. acetaldehyde, previously cooled at 6-7° C., 5 ml. of 25% potassium hydroxide in anhydrous methanol are slowly added. After addition of 100 ml. acetic anhydride the mixture is refluxed for 30 minutes. On cooling white crystals mixed with some resin precipitate. The mixture is filtered and the solids recrystallized from 1% acetic acid. Yield 27 g. (69%) 4'-cyanocinnamaldehyde, M.P. 135-137° C.

To a solution of 30 g. 4'-cyanocinnamaldehyde in 240 ml. glacial acetic acid previously heated to 35° C., 10.5 ml. bromine are added dropwise. When the addition is complete, 13.2 g. anhydrous potassium carbonate are added and the mixture is refluxed for 30 minutes. After cooling the crystals are collected in vacuo and recrystallized from anhydrous ethanol. Yield 42 g. (94%) of 4'-cyano- α -bromocinnamaldehyde, M.P. 156-157° C.

We claim:

1. A compound of the formula

wherein X is a member of the class consisting of a sulfur atom and the vinylene group.

4

2. α -Bromo-4'-cyanocinnamaldehyde.
3. α -Bromo- β -(5-cyano-2-thienyl)-acrolein.
4. A pharmaceutical composition for combatting topical bacterial and fungal infections, comprising from about 0.1 to about 10% of a compound of the formula

10 wherein X is a member of the class consisting of sulfur and the vinylene group, and a physiologically acceptable diluent.

15 5. A pharmaceutical composition for combatting topical bacterial and fungal infections, whose active component consists essentially of a compound of the formula

20 20 wherein X is a member of the class consisting of sulfur and the vinylene group.

25 6. A pharmaceutical composition for combatting topical bacterial and fungal infections, whose active component consists essentially of α -bromo-4'-cyanocinnamaldehyde.

30 7. A pharmaceutical composition for combatting topical bacterial and fungal infections, whose active component consists essentially of α -bromo- β -(5-cyano-2-thienyl)-acrolein.
